UNITED STATES PATENT OFFICE.

JESSE B. JOHNSON, OF INDIANAPOLIS, INDIANA.

CAR-TRUCK.

SPECIFICATION forming part of Letters Patent No. 447,430, dated March 3, 1891.

Application filed August 6, 1890. Serial No. 361,176. (No model.)

To all whom it may concern:

Be it known that I, JESSE B. JOHNSON, of Indianapolis, county of Marion, and State of Indiana, have invented certain new and useful Improvements in Car-Trucks; and I do hereby declare that the following is a full, clear, and exact description thereof, reference being had to the accompanying drawings, in which like letters and figures refer to like parts.

My invention relates to improvements in the construction of trucks for street-cars and will be understood from the following description.

15 In the drawings, Figure 1 is a vertical section of my device, the axle and wheel being partially broken away. Fig. 2 is an inside end view of a modified form of the device shown in Fig. 1. Fig. 3 is a section on the line $\alpha\alpha$, Fig. 1. Fig. 4 is an enlarged detail view of the T-spring. Fig. 5 is a side view of the double pawl.

In detail, a is the axle, which is shouldered in the rear at 1 and in front at 2, as shown.

25 b is a taper boxing, which is shrunk on the axle at the rear, its end abutting the shoulder 1, and about this is a metal lining l and in front is a similar lining l' , which rests upon the tapered bushing b' , which is keyed to the 30 axle a . The hub h of the wheel w moves directly upon these metal linings l l' . r r' are metal dust rings or collars, which are shrunk upon the hub, covering the joint of the metal linings.

35 o is an oil-chamber having an outlet through the hub, which is closed by the screw-pin s .

c is a collar or washer, which has openings or seats for the keys k , and between these keys fits loosely upon the axle.

40 k are keys, which are seated in grooves in the axle passing through the collar c and the nut-ring n , the threads of this nut engaging with similar threads formed on the outer faces of the keys, and when turned down 45 tight the nut is locked by means of the set-screws s , which bear upon small blocks g , set in the screw-holes and resting on the keys, preventing the nut from working loose, while the keys perform the same office for the collar c , and the end of each key abuts against the shoulder 2 of the axle, as shown in Fig.

1. The collar c , having notches which fit down over the keys k , cannot move, and therefore the friction of the wheel against this collar has no effect whatever upon the ring-nut 55 n and cannot move it.

If either the tapering inner face of the hub h or of the brass linings l l' should become worn, the outer tapering sleeve or boxing b' can be forced in by turning the ring-nut n , 60 this boxing thus operating as a wedge, and this will tighten the parts and take up any lost motion which arises from such wear. When the nut is turned, the pressure of the collar or washer c throws the tapering sleeve 65 b' directly in, and the same operation forces the rear part of the hub back against the tapering sleeve b and back upon the brass lining l . Thus the wear on either side is entirely compensated and taken up by turning the 70 nut. Of course the set-screws s are to be first loosened, and when the nut has been turned sufficiently these are to be tightened, locking the parts in place, and this is accomplished without moving the wheel from its proper 75 relative position, keeping it always upon the track and preventing its derailment. The opening o serves not only as a reservoir for oil, but affords room for the pushing back of the tapering sleeves for tightening the parts. 80 The tendency of the oil is to work out of this chamber along the face of the linings l l' and out at the joint beneath the rings r r' , and this movement of the oil acts also to prevent dust from entering at those points, thus over- 85 coming a serious difficulty heretofore met in the use of a wheel which is loose upon the axle.

In Fig. 2 I show a modification of the device which is adapted to be used upon cars 90 propelled by motors where the power is connected directly to the axle. In this case the interior arrangement is similar to that shown in Fig. 1; but the rear dust-ring r is toothed on the outside, forming a ratchet-wheel, 95 (shown at r^2 in Fig. 2,) and the boxing b has a projection or ear e , which extends upward, and to this is bolted a T-spring 6 , (shown in Fig. 4,) having shoulders 7 and a latch 8 , forming notches to receive the arm of the double 100 pawl, as hereinafter described. Behind this T-spring is an arm 3 , to which is connected

below a double pawl $p p$, which is pivoted to the ear of the boxing b , these pawls being adapted to engage alternately with the notches of the ratchet-wheel r^2 . In Fig. 2 the right-hand pawl is shown as engaging with the ratchet-wheel, the car wheel and axle a moving in the direction of the arrows, and of course as the car-wheel moves the boxing b moves with it and the ratchet-wheel, so that it will turn with the axle until a curve is reached.

In rounding a curve the ordinary car-wheel, being rigid on the axle, will slip and grind against the side of the rail, cutting away the wheel-flange and the rail, while in my device, the car-wheel being normally loose on the axle and only locked by the pawl mechanism herein described, the wheel will then move faster than the axle and slip away from the pawl, and the latter will drop into notch after notch of the ratchet-wheel until the curve is passed, when the movement of the wheel will again equal that of the axle, and the wheel will be locked to the axle by means of the pawl. Of course this pawl-and-ratchet mechanism is unnecessary where cars are pulled by cables or horses, for in such case the power is not applied directly to the axle of the wheel. It is only necessary upon a motor-car where power is applied to the axle. Therefore the trailers of an electric railway need not be equipped with the pawl and ratchet. When a car thus equipped has reached the end of the line or when the car is to be backed and run in an opposite direction, the operator takes hold of a lever connected with the car and throws the stop $s t$ (shown in the full lines in Fig. 2) over to the second position shown in the dotted lines to the left. In this movement it will strike the arm 3 at about the point shown in the intermediate dotted lines, and as it moves on it carries with it the arm 3 over to the position shown in the left dotted lines, where it enters the opposite notch in the T-spring, and this causes the pawl on the left-hand side to engage with the teeth of the ratchet r^2 , as shown in dotted lines in Fig. 2, and the car-wheel is again locked to the axle.

It will be understood that the shifting of the pawl can only be accomplished by the lever when the arm 3 is in position at the upper side of the wheel, so that it can engage with such lever, and inasmuch as it revolves with the axle during the greater part of its movement it is not in position to engage with such lever, and when the car has been stopped the operator would have to shift the pawls by hand; hence it is advisable to shift the pawls before the car stops and when the arm 3 is in proper position to engage with the lever.

The locking mechanism herein shown might be used with straight instead of taper boxings, and I do not intend to limit myself to the use of this locking mechanism to taper boxings alone. The first part of my invention

therefore relates to the use of a car-wheel loosely mounted and revolving upon the axle, and of adjustable boxings for taking up the lost motion occasioned by the wear of parts, and means for preventing these parts from getting loose, while in the second place I provide a pawl-and-ratchet mechanism for locking the loose wheel to the axle and thus causing it to revolve with it, where the power must be applied directly to such axle.

What I claim as my invention, and desire to secure by Letters Patent, is the following:

1. In a car-truck, the axle a , shouldered at 1 and 2, as shown, the adjustable taper boxing b , rigidly connected to such axle behind, and the taper bushing b' , keyed to such axle in front of the wheel, metal linings $l l'$, superimposed about such boxing and bushing, dust-rings $r r'$, shrunk upon the opposite sides of the wheel-hub, the wheel adapted to revolve upon such boxings, an oil-chamber formed in the hub thereof, with means, such as a lock-nut and washer, for securing the parts in place, all combined substantially as shown and described.

2. In a car-truck, an axle a , a taper boxing b , and bushing b' secured thereon, a wheel w , adapted to revolve upon such taper bushing and boxing, and a ratchet and double pawl mechanism connected thereto for alternately locking the wheel to the axle on the opposite sides, all combined substantially as shown and described.

3. In a car-truck, an axle, taper boxings rigidly connected thereto, a wheel loosely mounted on such boxings, metallic linings interposed between the wheel and such boxings, and means, such as a lock-nut and washer, for holding the parts in place and taking up the lost motion occasioned by wear, all combined substantially as shown and described.

4. A car-truck wherein the wheel revolves upon taper boxings rigidly connected to the axle in the rear and detachably connected to the axle in front, with means, such as a lock-nut, operating upon keys whose outer faces are threaded, and a washer loosely mounted on the axle for taking up lost motion occasioned by the wear of the parts, all combined substantially as shown and described.

5. A car-truck wherein the wheel revolves upon a boxing rigidly connected to the axle in the rear, and a bushing detachably connected to the axle in front, a washer loosely mounted on such axle outside such bushing, with means, such as a lock-nut, operating upon keys whose outer faces are threaded, such keys passing through such washer and keying the bushing to the axle for taking up lost motion occasioned by the wear of the parts, all combined substantially as shown and described.

6. In a car-truck, an axle, a boxing rigidly connected thereto behind the wheel, a bushing keyed to such axle in front of the wheel,

a wheel loosely mounted on such boxing, and
means, such as a lock-nut and washer, with
keys threaded upon the outside for engaging
with such nut for holding the parts in place
5 and taking up lost motion occasioned by
wear, all combined substantially as shown
and described.

In witness whereof I have hereunto set my
hand this 1st day of August, 1890.

JESSE B. JOHNSON.
